(57) **CLAIM**

The ornamental design for a display screen or portion thereof with animated graphical user interface, as shown and described.

DESCRIPTION

FIG. 1 is a front view of a first image of a display screen or portion thereof with animated graphical user interface showing my new design;

FIG. 2 is a front view of a second image thereof;

FIG. 3 is a front view of a third image thereof; and,

FIG. 4 is a front view of a fourth image thereof.

The claimed subject matter of FIG. 2 is shifted slightly to the left relative to its position in FIG. 1. The claimed subject matter of FIG. 3 is shifted slightly to the right relative to its position in FIG. 1. The appearance of the transitional image sequentially transitions from FIG. 1 to FIG. 2, then repeatedly transitions between the images shown in FIGS. 2 through 3. The process in which one image transitions to another image forms no part of the claimed design. The period during which FIG. 1 transitions to FIG. 2 forms no part of the claimed design. The transitional image transitions repeatedly between FIGS. 2 and 3, with the number of repeated transitions and speed of transition being sufficient to create the blurred appearance shown in FIG. 4.

The broken lines showing a display screen or portion thereof is included for the purpose of illustrating the article and form no part of the claimed design. The broken lines within the display screen represent graphical elements and form no part of the claimed design.
